INVENTORS,
BY *John Moore*
ATTORNEY.

UNITED STATES PATENT OFFICE.

WALLACE B. CURTIS AND GEORGE M. DONNALLY, OF POMEROY, OHIO.

DESIGN FOR A LAMP-SHADE.

SPECIFICATION forming part of Design No. 22,996, dated January 2, 1894.

Application filed November 10, 1893. Serial No. 490,584. Term of patent 14 years.

To all whom it may concern:

Be it known that we, WALLACE B. CURTIS and GEORGE M. DONNALLY, citizens of the United States, residing at Pomeroy, in the county of Meigs and State of Ohio, have invented a certain new and useful Design for Lamp-Shades, of which the following is a specification, reference being had therein to the accompanying drawings.

Our invention is a new and original design for a lamp shade, and the leading feature of our design is a shade of substantially a pear shape.

We have illustrated our design in the accompanying drawings, in which—

Figure 1 represents a side view of our shade, and Fig. 2 is a similar view taken at a right angle to Fig. 1.

Our design consists of the shell shaped sections A, forming the pear, egg or oval shaped

shade. The edge of the shade is formed with the bead ornamentation B in the form of short continuous curves; and the outer face ornamentation in the form of flutes or corrugations C which lead from the bead ornamentation to the top of the shade and gradually decrease in width from the base to the top of the shade, the whole forming a shade of pear shape having the appearance of a shell.

We claim—

The design for a lamp shade herein shown and described.

In testimony whereof we affix our signatures in presence of two witnesses.

WALLACE B. CURTIS.
GEORGE M. DONNALLY.

Witnesses:

CHAS. D. HOPKINS,
C. E. PEOPLES.
